ISAAC DE KAISER, OF WILKINSBURG, AND ARTHUR G. POPCKE, OF PITTSBURGH, PENNSYLVANIA.

SUBTERRANEAN-WELL HEATER.

Application filed March 23, 1922. Serial No. 546,060.

To all whom it may concern:

Be it known that we, ISAAC DE KAISER, a citizen of the United States, and a resident of Wilkinsburg, in the county of Allegheny and State of Pennsylvania, and ARTHUR G. POPCKE, a citizen of the United States, and a resident of Pittsburgh, in the county of Allegheny and State of Pennsylvania, have invented a new and useful Improvement in 10 Subterranean-Well Heaters, of which the following is a specification.

Our invention relates to heating devices and particularly to devices for heat-treating subterranean wells.

15 One object of our invention is to provide a device of the above-indicated character that shall be simple and durable in construction, economical to manufacture and efficient in its operation.

20 Another object of our invention is to provide a subterranean well heater that shall be of easy manipulation and of ready and economical maintenance in service.

25 Another object of our invention is to provide a readily renewable fuel or heating material cartridge for a subterranean well heater to thereby simplify the operation of charging the heater in the field and to permit rapid recharging thereof if repeated heating operations are necessary or desired.

30 A further object of our invention is to so dispose a body of fuel or heating material in a subterranean well heater and to so direct or circulate a heat-increasing fluid therein as to improve the heat-giving property of the heater.

35 With such objects in view, as well as other advantages which may be incident to the utilization of the improvement, the invention consists in the parts and combinations thereof hereinafter set forth and claimed, with the understanding that the several necessary elements constituting the same may be varied in proportion and arrangement without departing from the nature and scope of the invention.

40 In our co-pending application, Serial No. 443,462, filed February 8, 1921, is fully set forth and described a subterranean well heater, similar to our present invention, together with a description of the operation thereof and the results accomplished thereby. The device is mainly adapted for lowering

into oil wells, the yield of which has decreased or stopped as a result of the accumulation of paraffin therein.

45 In practicing our invention, we propose to utilize a renewable fuse cartridge, to effect an improvement in the manner of supplying oxygen to the fuel and to so otherwise simplify and render more effective a subterranean well heater as to greatly facilitate and render more economical the operation of treating wells.

50 In order to make the invention more clearly understood, means are shown in the accompanying drawings for carrying the same into practical effect, without limiting the improvements, in their useful applications to the particular construction which, for the 55 purpose of explanation, we make the subject of illustration.

55 Fig. 1 of the accompanying drawings is a fragmentary longitudinal or side view, partially in elevation and partially in section, of a subterranean well heater embodying our invention.

60 Fig. 2 is a view taken along the line II-II of Fig. 1, and

65 Fig. 3 is a perspective view of a renewable fuel cartridge constituting a part of our invention.

70 A subterranean well heater embodying our invention comprises, in general, an outer shell or casing 1, a tube 2 by which the device is lowered into a well and through which combustion gases escape, a renewable fuel cartridge 3, an oxygen-containing tank or container 4 and a fluid-projecting member 5.

75 The casing 1 comprises upper and lower tubular sections 6 and 7, a union 8 for connecting the sections 6 and 7, a cap member 9 which fits the upper end of the section 7 and into which the tube 2 is fitted, and a lower end member 10. The tube 2 is adapted to extend only to a position above the water level in a well and to be connected, at its upper end, to a cable or sand line, as shown and described in our aforementioned co-pending application.

80 The renewable fuel cartridge 3 comprises a perforate tubular container, preferably of light sheet metal, having perforate end members 11 that are provided with perimetrical 85 spaced lugs or projections 12. The cartridge

3 is adapted to contain a combustible fuel, such as charcoal, coke, etc., that may be employed singly or intermixed, or that may be combined with a suitable heating material, 5 such as particles of fire-brick, asbestos or the like in any one of various combinations.

The lugs 12 serve to center the cartridge 3 in spaced relation to the walls of the section 6. A sleeve 14, closely fitting the lower 10 end of the section 6, is supported on the union 8 and, in turn, supports the cartridge 3 by engagement of the lower lugs 12 therewith.

The tank 4 is supported on the lower end 15 member 10 and is provided with a pressure regulator 15 and a control valve 16 between the tank and the member 5. The latter is provided with a nozzle 17 that is shaped to so direct an oxygen blast or draft circularly 20 and upwardly as to cause a helical whirl of oxygen around the cartridge 3 between the latter and the walls of the section 6. Since the walls of the cartridge are perforate, the fuel body in the cartridge is constantly surrounded by a fresh supply of oxygen to thereby quickly and effectively create an intense heat throughout a relatively great 25 length of the heater. The helical form of the oxygen whirl causes uniform distribution of the oxygen and, by causing it to travel a greater distance than it would travel if it were projected perpendicularly, causes it to more effectively combine with the fuel.

To further ensure perfect combustion, the 30 walls of the cartridge are constructed to offer as little obstruction to the free flow of oxygen around and through the fuel particles as possible, and are preferably constructed of combustible material to avoid obstructing the transference of heat to the 35 walls of the heater. A screen or perforate member of relatively thin sheet iron has been found to meet the above-mentioned requirements and is further well adapted for its 40 purpose because, after being consumed or oxidized, it retains its original shape sufficiently to permit the cartridge to be removed as a unit. However, we do not limit ourselves to the use of iron, as any other 45 suitable material may be used.

In operation, the cartridge 3 is placed in position in the section 6 and the tank 4 in the section 7 above ground, at a position sufficiently removed from the well mouth to 50 avoid igniting the well gases. An apertured pad or disk 18, of asbestos or other material, may be placed around the member 5 to insulate the tank 4 against undue heat. The regulator 15 is adjusted to give the desired 55 flow of oxygen and the valve 16 opened to permit the flow thereof.

When the cartridge 3 is ignited, the sections 6 and 7 are screwed together by the union 8 to, thus, totally enclose the casing 60 except for the outlet through the pipe 2.

This arrangement prevents the ingress of oil and water and renders the device absolutely safe for lowering into a well.

As described in our above-mentioned co-pending application, the device is lowered 70 into a well at the end of a sand or other line. Being submerged so far beneath the earth's surface, the heat generated in the heater is substantially all given off to the pumping 75 chamber of the well and the time of heating, being a matter of hours, ensures effective breaking down of the barrier which clogs wells having any considerable paraffin or other similar heavy constituents therein.

The device of our invention comprises few 80 parts, is compact, economical in construction and operation, is easy to transport and manipulate and, further, ensures a materially increased yield in producing wells that have been clogged by paraffin or have had 85 the production thereof stopped or retarded through any cause removable by heat.

We claim as our invention:

1. The combination with a heating device, 90 of a renewable fuel cartridge therefor adapted to supply one predetermined amount of heat only and comprising a container, and a body of solid fuel in the container.

2. The combination with a heating device 95 comprising a plurality of co-operating elements, of a renewable fuel cartridge therefor comprising a container adapted to be placed in the device in unattached operative relation to said elements, and a body of solid 100 fuel in the container.

3. The combination with a heating device, 105 of a renewable fuel cartridge therefor adapted to supply one predetermined amount of heat only and comprising a container having perforate walls, and a body of solid fuel in the container.

4. The combination with a heating device comprising a plurality of co-operating elements, of a renewable fuel cartridge therefor comprising a container adapted to be placed in the device in unattached operative 110 relation to said elements, and a body of solid-fuel particles in the container.

5. The combination with a heating device, 115 of a renewable fuel cartridge therefor comprising a cylindrical metal container embodying perforate permanently connected sides and ends, and a body of solid-fuel particles in the container.

6. The combination with a heating device, 120 of a renewable fuel cartridge therefor comprising a container constructed for operation with only one charge of fuel, and a body of solid-fuel particles in the container.

7. The combination with a heating device comprising a fuel chamber portion, of a renewable fuel cartridge therefor comprising a container having perforate walls and constructed for operative positioning in said 125

chamber in unattached relation to other elements in the device, and a body of solid fuel in the container.

8. The combination with a heating device comprising a fuel chamber portion, of a renewable fuel cartridge therefor comprising a container having perforate walls and adapted to be slipped into and from operative position in said chamber, and a body 10 of solid-fuel particles in the container.

9. In a subterranean well heater, the combination with a casing, and means for supporting combustion therein, of a renewable solid-fuel cartridge constructed in conformity, and to co-operate, with a portion 15 of the casing.

10. In a self-contained subterranean well heat generator, the combination with a casing and means for supporting combustion 20 therein, of a renewable solid-fuel cartridge constructed to fit the casing and to be slipped into position therein.

11. A heater comprising a casing that is totally closed except for a combustion-gas 25 outlet, a body of combustible material therein and means for supporting combustion and uniformly distributing a fluid against said combustible material.

12. In a subterranean well heater, the combination with a casing and a body of solid heating material therein, of means for heating said material, including means for directing a fluid uniformly thereagainst.

13. In a subterranean well heater, the combination with a casing and a body of solid particles of heating material therein, of means for directing and circulating a fluid to uniformly encompass said body and to enter the spaces between said particles to 35 effect uniform heating thereof.

14. In a subterranean well heater, the combination with a tubular casing, of a body of solid heating material disposed therein in spaced relation to the side walls thereof,

and means for causing a flow of fluid to said material in the space between said casing and said heating material.

15. A subterranean well heater comprising a tubular casing, a body of heating material therein, a fluid-containing tank and means connected to the tank and adapted to direct a whirling draft of fluid about said heating material.

16. A subterranean well heater comprising a tubular casing, a body of heating material disposed therein in spaced relation to the walls thereof, a fluid-containing tank, and means connected to the tank and adapted to direct a helical whirling draft of fluid around and along the body of the heating material in the space between the latter and the walls of the casing.

17. A subterranean well heater comprising a tubular casing, a body of combustible fuel therein, an oxygen-containing tank and means connected to the tank and adapted to direct a whirling draft of oxygen about said fuel.

18. A subterranean well heater comprising a tubular casing, a body of combustible fuel disposed therein in spaced relation to the walls thereof, an oxygen-containing tank and means connected to the tank and adapted to direct a helical whirling draft of oxygen around and along the fuel body in 75 the space between the latter and the walls of the casing.

19. A subterranean well heater comprising a tubular casing, a body of heating material disposed therein, a fluid source and 80 means connected to the source and adapted to direct a whirling draft of fluid along said body.

In testimony whereof, we have hereunto subscribed our names this 20th day of 85 March, 1922.

ISAAC DE KAISER.
ARTHUR G. POPCKE.
